UNITED STATES PATENT OFFICE.

CHARLES L. WAGANDT, OF BALTIMORE, MARYLAND, ASSIGNOR TO
NATIONAL ENAMELING & STAMPING CO., OF NEW JERSEY.

DESIGN FOR A GRATER.

SPECIFICATION forming part of Design No. 34,898, dated August 6, 1901.

Application filed July 5, 1901. Serial No. 67,250. Term of patent 3½ years.

To all whom it may concern:

Be it known that I, CHARLES L. WAGANDT, a citizen of the United States, residing at Baltimore, in the State of Maryland, have invented and produced a new and original Design for a Grater, of which the following is a specification.

Reference is to be had to the accompanying drawings, in which—

10 Figure 1 is a side elevation of the grater embodying the features of the design. Fig. 2 is a transverse section thereof on the line 2 2 of Fig. 1.

15 The design consists in the shape and configuration of the grater illustrated in the accompanying drawings, in which the body of the grater appears in the form of a truncated

cone having a plurality of roughened surfaces separated from each other by smooth surfaces. The roughened surfaces have different degrees of roughness, as shown, and taper in width from the larger toward the smaller end of the conical body, and a loop-handle appears on the smaller end of said body.

25 I claim—

The design for a grater herein shown and described.

In testimony whereof I affix my signature in the presence of two witnesses.

CHARLES L. WAGANDT.

Witnesses:

CHARLES L. VIETSCH,
FREDERICK S. STITT.
